AUGUSTIN ELLIS AND OLIVER ALBERTSON, OF SALEM, INDIANA.

Letters Patent No. 72,469, dated December 24, 1867.

IMPROVEMENT IN FENCES.

The Schedule referred to in these Letters Patent and making part of the same.

TO ALL WHOM IT MAY CONCERN:

Be it known that we, AUGUSTIN ELLIS and OLIVER ALBERTSON, of Salem, in the county of Washington, and State of Indiana, have made and invented a new and useful Improvement in Fences; and we do hereby declare that the following is a full, clear, and exact description thereof, which will enable those skilled in the art to make and use the same, reference being had to the accompanying drawings, and to the letters of reference marked thereon.

This invention relates to a new and improved portable fence, such as are designed to be readily put up and taken down. The invention consists in a novel application of braces or supports to the fence, and the manner of connecting the panels together, whereby a firm and substantial straight fence is obtained, and the "worm" or zigzag fence avoided. In the accompanying sheet of drawings—

Figure 1 is a side view of our invention.

Figure 2, a plan or top view of the same.

Similar letters of reference indicate like parts.

A A represent two panels of a fence, constructed of horizontal slats *a*, connected by vertical battens *b*, the latter being nailed or otherwise secured to the slats at both sides of the same. The end battens of the panels project beyond the ends of the slats, so that the panels may be lapped together and connected by pins, *c*, passing through them, the panels being in line with each other, so as to form a straight fence. To each side of each panel A there are attached blocks, B B'. These blocks are attached to the panels in pairs, the block B of each pair extending out further from the panels than the other ones, B', and having strips, C, attached to them by nails or otherwise. To each strip C, bars D are attached by pins *d*, or otherwise, and these bars D serve as bases to support the panels, the bars or bases resting upon the ground and forming a firm support for the fence, and fully obviating the necessity of placing the panels in a zigzag position in order that it may be securely retained in place.

Having thus described our invention, we claim as new, and desire to secure by Letters Patent—

The obliquely-projecting bars or bases D, attached to the panels A A, substantially in the manner as and for the purpose set forth.

AUGUSTIN ELLIS,
OLIVER ALBERTSON.
